(57) **CLAIM**

The ornamental design for a sock, as shown and described.

DESCRIPTION

FIG. 1 is a perspective view of a sock for a right foot illustrating my new design, the sock for the left foot being a mirror image thereof;

FIG. 2 is a front view thereof;

FIG. 3 is a rear view thereof;

FIG. 4 is a left side view thereof as referenced from the front view in FIG. 2;

FIG. 5 is a right view thereof as referenced from the front view in FIG. 2;

FIG. 6 is a top view thereof;

FIG. 7 is a bottom view thereof;

FIG. 8 is a front view of the sock in FIG. 1 with an alternative ribbon placement;

FIG. 9 is a front view of the sock in FIG. 1 with a second alternative ribbon placement;

FIG. 10 is a right side view of the sock in FIG. 1 with the lower ribbon removed; and,

FIG. 11 is a right side of the sock in FIG. 1 with the upper ribbon removed.
